Attorney.

UNITED STATES PATENT OFFICE.

WADE E. SACKNER, OF GRAND RAPIDS, MICHIGAN.

FORM.

Application filed February 12, 1923. Serial No. 618,499.

To all whom it may concern:

Be it known that I, WADE E. SACKNER, a citizen of the United States, residing at Grand Rapids, in the county of Kent and State of Michigan, have invented new and useful Improvements in Forms, of which the following is a specification.

The present invention relates to forms, particularly such as are employed for shaping and weaving thereover various kinds of woven articles, as lamp-shades, containers of various sorts, and the like; and its object is to provide such form of "knockdown" construction so that its members may be disassembled for compact storage or shipment, and particularly for ready removal from the finished woven articles of certain kinds.

This object is attained by, and the invention finds preferable embodiment in, the structure or structures hereinafter particularly described in the body of this specification and illustrated by the accompanying drawings, in which:—

Figure 1 is a top plan view of a portion 23 of a "knockdown" form;

Figure 2 is a side view of a portion thereof, sectioned at its left hand side on line 2— of Figure 1;

Figure 3 is an enlarged view of a portion 30 of the upper part of the same partially sectioned on line 3—3 of Figure 1;

Figure 4 is an enlarged view of a portion of the lower part of the same partially sectioned on the same line;

Figure 5 is a top plan view of a modified construction of the "knockdown" form, shown partially in section taken on line 5—5 of Figure 6;

Figure 6 is a side view of the same, sectioned at its left hand side on line 6 of Figure 5;

Figure 7 is a plan view of the separated halves of the lower supporting member of the form; and

Figure 8 is a sectional view of said halves taken on line 8—8 of Figure 7.

The form shown in Figures 1, 2, 3 and 4 comprises form members 1 and upper and lower supporting members 2, 3, laterally spaced apart, together with a connecting member—the centrally disposed rod 4—for detachably connecting the pair of supporting members 2, 3 together. These supporting members respectively have means for engaging the form members 1 adjacent their

ends to removably hold the form members in the angularly disposed relation seen in Figure 1, such means, as shown, being the circularly disposed sockets 5 in the supporting member 2 and the sockets 6 in the supporting member 3, respectively receiving the end portions 7 and 13 of the form members to hold the same in the angular relation shown in the views. The centrally disposed rod 4 detachably connects the supporting members together in said holding engagement with the form members, being connected detachably to at least one of the supporting members by suitable means, as by being passed through an opening 8 in the member 2 and secured by a pin or wedge 9 from reverse movement, and by being passed through an opening 10 in cross bar 11 of supporting member 3 and secured therein by a pin 12. It will be seen that the disposition of the sockets 5, 6 and the fitting therein of the end portions 7 (see Fig. 3) and 13 (see Fig. 4) holds the form members against turning movements in these sockets so that the form members are held edge outwardly in the structure's assembled position shown; it will be seen also that the extensions 20 (see Fig. 3) and 21 (see Fig. 4) extending under the supporting member 2 and behind the supporting member 3 respectively, provide a locking engagement therewith, holding the form members against outward-radial or disassembling movement. In Figure 4, the end portion 13 held in the socket 6 is also the extension 21 locking the form member 1 at its lower end against disassembling movement and also holding against turning movement in the socket 6.

In Figures 5, 6, 7 and 8 a modified construction of the form is shown, in which views parts corresponding to parts in the other views are designated by the same reference characters with the addition of a prime mark.

In this modified construction however, the form is especially adapted for weaving thereover an article, as a container, having a neck of less diameter than the middle portion of said article. That the parts or members of this modified construction may be disassembled after the article is woven thereover and may thus be readily removed from its interior, the lower ends 13¹ of the form members 1¹ are seated in radially extending sockets 6¹ formed in the lower supporting

member 3¹ which comprises separable halves 14, 14 having mutually overlapping portions 15 provided with registering openings 10¹ therethrough, through which registering 5 openings the rod 4¹ is removably inserted in the assembled position of the parts and is withdrawn therefrom when the work is completed, thus permitting the halves 14 to separate and the form members 1¹ to be 10 assembled, whereupon all the parts of the structure may be withdrawn from said finished article's interior.

It will be understood that the article 15 formed and shaped by the form is made of suitable fabric woven around and in contact with the outer edges of the form members in both constructions illustrated.

The invention being intended to be pointed out in the claims, is not to be limited to 20 or by details of construction of the particular embodiment or embodiments thereof illustrated by the drawings or hereinbefore shown or described.

I claim:—

- 25 1. In a structure of the character described; a plurality of form members; a pair of laterally spaced supporting members respectively having means engaging the form members adjacent their ends for removably holding the form members in angularly spaced relation; a centrally disposed rod detachably connecting the supporting members in their holding engagement with the form members.
- 35 2. In a structure of the character described; a plurality of form members; a pair of laterally spaced supporting members respectively having means engaging the form members adjacent their ends for removably 40 holding the form members in angularly spaced relation, at least one of the supporting member's said means being adapted to hold an end of each form member against outward radial movement; a centrally disposed rod detachably connecting the sup-

porting members in their holding engagement with the form members.

3. In a structure of the character described; a plurality of form members; a pair of laterally spaced supporting members respectively having angularly disposed sockets adapted to removably receive the ends of the form members, the sockets of at least one of the supporting members being also adapted to hold the form members at one of their ends against outward radial movement; a centrally disposed rod detachably connecting the supporting members in their holding engagement with the form members. 55

4. In a structure of the character described; a plurality of form members; a pair of laterally spaced supporting members respectively having angularly disposed sockets adapted to removably receive the ends of the form members, the sockets of at least 60 one of the supporting members being also adapted to hold the form members against turning movement therein; a centrally disposed rod detachably connecting the supporting rod members in their holding engagement with the form members. 70

5. In a structure of the character described; a plurality of form members; a pair of laterally spaced supporting members respectively having means engaging the 75 form members adjacent their ends for removably holding the form members in angularly spaced relation, at least one of the supporting members comprising separable halves having mutually overlapping portions provided with registering openings therethrough; a centrally disposed rod detachably connecting the supporting members and removably inserted into said openings in the assembled position of said halves. 80

In testimony whereof I have hereunto set my hand at Grand Rapids, Michigan, this 8th day of February, 1923.

WADE E. SACKNER.
